United States Patent

Des. 238,482
Patented Jan. 20, 1976

238,482

POWER WINCH

Dallas L. Pitts, Wynne, Ark., assignor to
Pitts Drive, Inc., Wynne, Ark.

Filed Apr. 17, 1974, Ser. No. 461,616

Term of patent 14 years

Int. Cl. D12—05

U.S. Cl. D12—54

FIG. 1 is a front elevational view of a power winch showing my new design;

FIG. 2 is an end elevational view thereof, the opposite end being a mirror image of the end shown herein;

FIG. 3 is a top plan view thereof; and

FIG. 4 is a bottom plan view thereof.

I claim:

The ornamental design for a power winch, substantially as shown and described.
